UNITED STATES PATENT OFFICE

2,621,226

SOCKET FOR LIGHTHOUSE TUBES

William H. Conron, Haddonfield, and Frederick H. Schneider, Westville, N. J., assignors to Radio Corporation of America, a corporation of Delaware

Application April 21, 1948, Serial No. 22,435

1 Claim. (Cl. 173—328)

1

This invention relates to improvements in supports for electron tubes and has for its principal object to provide a rapidly detachable, non-microphonic, socket assembly of low electrical impedance for electron tubes, and particularly tubes of the so-called "lighthouse" variety.

The invention is described in connection with the accompanying drawing, wherein:

Fig. 1 is a top plan view, Fig. 2 a sectional elevation and Fig. 3 an exploded view of a socket and tube assembly constructed in accordance with the principle of the invention.

The electron tube to which the invention is here applied is a JAN and RCA type 2C-40 "lighthouse" tube. The tube comprises a metal body portion 1 of stepped construction having an insulating base 2 at one end and, at its opposite end, terminates in a prong 3 through which energizing current is applied to an internal anode (not shown). The base 2 of the tube is provided with a centering pin 4 and a number (in this case, six) of prongs 5 arranged in circumferentially spaced relation about the said pin 4. Two of the prongs 5 are filament leads; another is a D. C. grounding terminal for the cathode and the rest are "dummies" whose only useful purpose is to aid in retaining the base of the tube in a wafer-like socket 6. Three upstanding metal tongues 7 which will be understood to be connected within the wafer to the live terminals of the socket provide convenient binding posts for the flexible wires 8 that supply current for the filament and a D. C. return for the cathode. The treads or steps 1a and 1b on the body of the tube, near the base 2, are constituted of metal and serve as R. F. grounding connectors for the cathode. Another "step" or flange 1c, which may extend radially outward from the body of the tube, comprises a grid connector. This third flange-like step 1c is insulated from the steps 1a and 1b, and from the anode terminal 3, by glass or other insulating inserts 9 and 10, respectively.

The wafer-like socket 6 within which the prongs 5 on the base of the tube are received is provided with a number (in this case, three) of radially extending arms 11 to which a similar number of arcuate-shape leaf springs 12 are respectively affixed as by rivets 13. The other end of each spring 12 is similarly affixed, as by a rivet 14, to the flat "upper" surface of a cup-shape locking ring 15. This ring or annulus 15 is provided on its rim 15r with a bayonet slot 16 for engagement with a complementary bayonet pin 17 on the rim 18r of a hollow metal pedestal 18

2

upon which the first step 1a of the tube is adapted to rest and within which a portion of the body of the tube is adapted to be received.

The pedestal 18 upon which the locking ring 15 is adapted to be removably affixed preferably comprises a solid-metal cylinder, open at both ends, and secured at its lower end as by screws 19 to an insulating panel or plate 20 which is provided with an aperture 20a through which the free end of the tube 1 may project. Another insulating plate or panel 21 beneath the panel 20 serves as a convenient support for a metal jack 22 which receives the prong-like anode terminal 3 of the tube.

As shown more clearly in Fig. 3, the inner surface of the metal cylinder or pedestal 18 contains a multiplicity of inwardly extending circumferentially arranged spring-metal fingers 23 upon which the second or "cathode flange" 1b of the tube 1 is adapted to bear, and the aperture 20a of the insulating panel 20 contains a similar set of spring-fingers 24 for the third or "grid" flange 1c of the tube. It will be observed upon inspection of Fig. 2 that when the tube has been entered into and locked on the pedestal, the springs 12 which connect the socket 6 to the locking ring 15 are under tension and therefore bias the cathode and grid flanges 1b and 1c of the tube into intimate contact with the spring fingers 23 and 24, respectively. The counterbiasing forces applied to the tube by the socket springs 12 and by the spring fingers 23 and 24 not only provide a non-microphonic support for the tube but also ensure a contact of low electrical impedance 35 between the said fingers and the flanges 1b and 1c of the tube.

From the foregoing it will be apparent that the present invention comprises a rapidly detachable, non-microphonic, socket assembly of low electrical impedance and one especially suitable for electron tubes of the so-called "lighthouse" variety.

What is claimed is:

A non-microphonic support for an electron tube of the type comprising a body portion having at least one radially extending electrode terminal thereon and a base portion from which a plurality of axially extending prong-like electrode terminals protrude, said support comprising a pedestal having a bore for receiving said tube body portion and having electrical connector means mounted thereon, said electrical connector means being disposed within said bore in a position to engage said radially extending electrode terminal, a socket member having means

for engaging said prong-like electrode terminals, means for resiliently and removably connecting said socket to said pedestal, said last mentioned means including a locking member for engagement with said pedestal and spring means comprising a plurality of arcuate shape leaf springs which extend in a circumferential direction about the axis of said locking member, said spring means interconnecting said socket and said locking member thereby to apply a biasing force on 10 said tube through said socket to hold said radially extending electrode terminal intimately in contact with said electrical connector means.

WILLIAM H. CONRON.

FREDERICK H. SCHNEIDER. 15
